UNITED STATES PATENT OFFICE

2,453,621

ILLUMINATED COMPACT

Orville W. Chinn, Lexington, Ky.

Application April 24, 1947, Serial No. 743,505

1. Claim. (Cl. 240—6.45)

1

This invention relates to improvements in ladies' vanity accessories particularly compacts and the like.

An object of this invention is to provide an improved device for carrying cosmetics and illuminating the face of the user in the application thereof.

Another object of this invention is to provide means for illuminating a certain predetermined area.

A further object of this invention is to provide means for controlling the illumination emitted therefrom.

Another object of this invention is to provide means for rendering the illuminating means accessible.

A still further object of this invention resides in the provision of cosmetic retaining means.

Another object of this invention is to provide a compact, efficient and inexpensive device of the character described which will lend itself well to commercial manufacture.

Other objects and features of novelty shall become readily apparent to those skilled in the art or will be specifically pointed out in following the description of a preferred embodiment of the instant inventive concept illustrated in the accompanying drawings, wherein:

Figure 1 is a plan view of the instant invention showing the lid in an open position;

Figure 2 is a side view of the invention shown in Figure 1;

Figure 3 is a fragmentary sectional view of the invention shown in Figure 1 and taken substantially on the line 3—3 thereof and in the direction of the arrows;

Figure 4 is a fragmentary sectional detail view taken substantially on the line 4—4 of Figure 3 and in the direction of the arrows;

Figure 5 is a transverse sectional view of the invention shown in Figure 1 and taken substantially on the line 5—5 thereof and in the direction of the arrows;

Figure 6 is a longitudinal sectional view of the invention and taken substantially on the line 6—6 of Figure 1 and in the direction of the arrows;

Figure 7 is an enlarged fragmentary sectional view of the battery retaining means which serves the function of a portion of an electrical circuit, and

Figure 8 is a schematic wiring diagram of the electrical circuit used in conjunction with the present invention.

Referring now in detail to the illustrated pre-

2

ferred embodiment of the instant invention, like reference characters are used to indicate similar parts throughout.

This invention has been conceived due to the difficulties arising from trying to apply cosmetics in dark places such as taxicabs, automobiles (during the night hours), poorly lighted quarters and the like.

A case 10 is divided into two chambers 12 and 14 by a suitable transverse cross member 16. A door 18 is swingingly received on said case by means of a suitable hinge 20 secured thereto. A friction latch 22 is received on said door opposite the hinge 20 and is adapted to engage a keeper or protuberance 24 secured to or formed integral with said case. A mirror 26 or some other suitable reflecting means is secured to the inner surface of the door 18 and a flange 28 is provided on the periphery of said door. This flange is adapted to be received within the case 10 in order to form an effective seal therebetween.

An applicator 30 is adapted to be received in the aperture 12 and is retained therein by the engagement of the knob 32 with the mirror or reflecting means 26 when the device is in its closed position.

Referring now to the chamber 14, a lid 34 is hingedly received on the inner face of the said case 10. Any suitable type of hinge may be used, the simple pivot pin 36 being preferable however. A cantilever arm 38 having a socket 40 at the end thereof is provided on the inner face of the case 10 and within the chamber 14. A bulb or lamp 42 is conventionally received in the said socket 40. Secured to the said socket is a reflector 44 adapted to project light rays through an appropriate aperture 46 in the said door 34. A lens 48 may be provided over the said aperture 46 if so desired. A suitable friction latch 50 is received on an edge of the said door 34 and is adapted to engage the transverse cross member 16.

A pair of friction clamps 52 are received in oppositely disposed relation within the chamber 14 and are adapted to removably secure batteries 56 therein. The said clamps 52 may be secured to the floor of said case by any suitable means such as rivets 58 and the like. A pair of clamps 60 are provided at opposite ends of the said chamber 14 and are adapted to receive the front and back ends of batteries in frictional engagement. A second pair of clamps 62 are provided adjacent the center of said chamber 14 and are adapted to engage the free back and front ends of batteries 56 for frictional engagement therewith. The said pairs of clamps 60 and 62 are in-

sulated from the said housing 10 by a suitable block of insulation 64 in order that they may be electrically free of said case. It is apparent from an inspection of Figure 5 that the above discussed clips 60 and 62 are in an electrical circuit comprising a first battery, a clip 60, a conductor 66 extending to a suitably insulated slide 68, thence a switch 70, a second slide 72 and a conductor 74 which joins the second of said pair of clips 60. Obviously, the circuit breaker 10 is used to energize and de-energize the lamp 42.

A schematic showing of the wire diagram is seen in Figure 8. It is apparent that the said circuit including all of its associated elements is accessible by merely lifting the said lid 34.

If desired, a peripheral flange may be provided about and extending from the said flange 28 and a reflecting material such as chromium plate or the like may be applied thereto in order to reflect light on the mirror surface.

There has been illustrated but a single preferred embodiment of the instant invention, however, it is apparent to those skilled in the art, that various changes including omissions and additions may be made herein without departing from the spirit of the invention. Accordingly, limitation is sought only in accordance with the scope of the appended claim.

Having thus described this invention what is claimed as new and novel is:

In an illuminating compact the combination of a case, a first chamber in said case adapted to receive cosmetics therein, a second chamber in said case, a hingedly mounted lid thereover, a

plurality of dry cells spaced apart and located in said second chamber, friction clamps for securing said cells in said second chamber, a socket located between the cells and adapted to receive an illuminating means in said second chamber, a transparent member on said lid and in alignment with said socket, an electrical circuit in said second chamber, a manually operated circuit breaker secured to said lid and forming a part of said electrical circuit, a bracket attached horizontally to said case and supporting said socket, a block of insulating material in said second chamber and between the cells; said circuit including a resilient contact attached to said block and engaging one of said cells and one contact of said socket and a second resilient contact mounted on said block and engaging the second contact of said socket and the other cell, and closure means on said case having latching means thereon.

ORVILLE W. CHINN.
